CHARLES R. KINKAID AND EMIT T. SHREVE, OF ROTAN, TEXAS.

VALVE-ACTUATING MECHANISM.

Application filed June 7, 1926. Serial No. 114,358.

Our present invention has reference to valve actuating means, and our object is the provision of a means for silencing the contacting engagement between the tappet and a valve stem.

A further object is the provision of a tappet for internal combustion engine valves of a construction to insure the proper alignment of the parts constituting the tappet, cushioning means between such parts, means for holding the tappet screw in proper contacting engagement with the valve stem, and means for lubricating the parts comprising a tappet for insuring the free movement thereof through the tappet guide.

To the attainment of the above broadly stated objects and others which will present themselves as the nature of the invention is better understood, the improvement further resides in certain other novel features of construction, combination and operative association of parts, a satisfactory embodiment of which is illustrated by the drawings which accompany and form part of this application.

In the drawings:

Figure 1 is a side elevation of our improvement, with parts being in section.

Figure 2 is a top plan view of the lower or head member of the tappet.

In Figure 1 of the drawings, the valve 1 is seated and has its stem 2 received through a suitable guide. The valve is retained seated through the medium of the usual spring 3 whose outer end is arranged upon a spring seat 4 secured on the stem 2 in the usual manner.

Below the stem there is the usual tappet guide 5, and movable through this guide there is a tappet or valve lifter that forms the subject matter of this invention.

The improvement comprises a lower member or section 6 having a disc head 7 to be engaged by the engine cam 8. The head, at its juncture with its body is formed with an inwardly rounded neck 9 and has, adjacent its outer end, an annular depression 10. The sides of the body has longitudinally extended substantially V-shaped oil grooves 11 which communicate with the depression 10 and with the neck 9. On its outer end the

body of the member 6 is provided with outstanding pins 12 and with a compressible disc 13. Secured on the said outer end of the tappet section 6, and passing through the ring disc 13 there is a coil spring 14. This spring is received in a central bore in the outer tappet section 15. The section 15 is provided with openings 16 that receive the pins 12 therein and screwed in the bore of the tappet section 15 and contacted by the spring 14 there is the tappet screw 17. On the outer end of the screw 17 there is a nut or head 18, and also threadedly engaging the tappet screw and resting on the outer end of the tappet section 15 there is a lock nut 19.

The spring 14 influences the tappet section 16 and the screw 17 thereon into proper contacting engagement with the valve stem 2. The pins 12, in the tappet section 6, received in the openings 16 in the tappet section 15, will insure a proper longitudinal alignment of both sections, while the ring gasket 13 serves as a cushion to absorb any jar and noise created thereby incident to the sections being brought toward each other. The tappet screw may be readily adjusted in the tappet, and with a tappet or valve lift as above described we have found from practical experience that valves will be properly operated for an indefinite period of time without any shock or jar and consequent knocking between the tappet parts 85 and the valve stem.

Having described the invention, we claim:—

A valve lift comprising a tappet and a guide therefor, said tappet including two sections, one to be engaged by the cam of the engine and the other to engage with the valve stem of the engine, said first mentioned section having a body portion received in the guide and having a head portion to be contacted by the cam, said body portion having a reduced neck at its juncture with the head and an annular groove adjacent to its outer end, said body having longitudinal oil grooves therethrough, pins extending from the outer end of the said section, the second tappet section having a portion of its body received in the guide and having openings for the reception of the

pins, a compressible ring gasket between the tappet sections, a tappet screw threaded in the bore of the last mentioned tappet section, a binding nut thereon contacting with

5 said section and a spring received in the bore of the last mentioned tappet section, contacting with the end of the screw there-

in and also contacting with the first mentioned tappet section.

In testimony whereof we affix our signatures.

CHARLES R. KINKAID.
EMIT T. SHREVE.
